[57] CLAIM

The ornamental design for table, as shown and described.

DESCRIPTION

FIG. 1 is a perspective view of a table showing my new design;

FIG. 2 is an elevational view showing one of the four identical sides;

FIG. 3 is a top plan view thereof;

FIG. 4 is a bottom plan view thereof;

FIG. 5 is a perspective view of a table, showing a second embodiment of my new design;

FIG. 6 is a perspective view of a table, showing a third embodiment of my new design;

FIG. 7 is an end elevational view of the third embodiment; and,

FIG. 8 is a bottom plan view of the third embodiment.
